UNITED STATES PATENT OFFICE.

ROBERT NAWRATH, OF NEWARK, NEW JERSEY, ASSIGNOR TO THE VALE BARREL MACHINE COMPANY, LIMITED, OF HAMILTON, CANADA.

BARREL-MACHINE.

SPECIFICATION forming part of Letters Patent No. 591,003, dated October 5, 1897.

Application filed October 30, 1895. Serial No. 567,427. (No model.)

To all whom it may concern:

Be it known that I, ROBERT NAWRATH, a subject of the Emperor of Germany, residing at Newark, in the county of Essex and State of New Jersey, have invented certain new and useful Improvements in Barrel-Machines; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

15 The objects of this invention are generally to set the staves of a barrel in position to secure the usual cylindrical form; to enable the ends of said staves to be trimmed by chamfering, grooving, and crozing while said staves are in such position; to admit of the application of certain hoops, known as the "truss-hoops," by which said staves are held in position before removal from the machine; to facilitate the operation of assembling the parts, and to reduce the cost of construction.

More specific objects of the invention are to so hold the staves in position as that when turning out the grooves in which the barrel-heads are secured said staves will not spring out of position with parts of the machine, and thus cause the turning-tool to produce a spiral groove rather than a true circle, as in certain machines heretofore experimentally produced; to provide the cylinder over which the staves are arranged when forming the body of the barrel with greater strength to resist the strain brought to bear thereon when said staves are fed to the machine; to facilitate the operation of fastening the staves last fed to the machine in place; to provide a more firm and secure support for the cutters when in position for operation upon the staves, whereby a more smooth and even cut is effected and the danger of bending or twisting the cutter-shaft avoided, and to secure other advantages and results, some of which will be referred to hereinafter in connection with the description of the working parts.

The invention consists in the improved barrel-forming machine and in the arrangements and combinations of parts, all substantially

as will be hereinafter set forth, and finally embraced in the clauses of the claim.

Referring to the accompanying drawings, in which like letters and figures indicate corresponding parts in each of the several views, Figure 1 is a front elevation of the improved machine, showing the general relations of the various parts. Fig. 2 is a side elevation of a collapsible frame over which the barrel is formed. Fig. 3 is a section of the same, taken at line *x*. Fig. 4 is a detail elevation of portion of a feed-roller shaft, and Fig. 5 is an end view of a coupling-piece for the same. Fig. 6 is a sectional view of the frame, showing the parts in their collapsed relations, the section being taken on line *x*. Fig. 7 is a section taken at line *y*. Fig. 8 is a central longitudinal section of said collapsible frame enlarged. Fig. 9 is a side view of a portion of the machine, showing the means for fastening the staves finally inserted to complete the barrel-body. Figs. 10 and 11 are details showing the construction of a shifting cutter for trimming the edge of the barrel; and Figs. 12, 13, and 14 are respectively a side view, a plan, and a view of a preferred arrangement of cutters for forming the groove, croze, and chamfer at the edges of the said barrel.

In said drawings, *a* indicates a suitable bed-plate, having stands *a'a'*, providing boxes or bearings for a driving-shaft *b*, and having projecting bearings *a''* for driving-shaft supports *c c*, which latter are connected so as to work to and from the shaft *b* simultaneously and together. Said bed-plate also has bearings *a'''* for a saw-spindle-driving shaft *d*. On said bed-plate is also fastened a carrier *e*, provided with slideways *f*, in which certain slide-pieces *g* of "sweeps" *h h h* work horizontally, the said sweeps being adapted to lie outside of and around the barrel and to guide the staves into position as they are fed to the machine. Said sweeps are in positions to give, in connection with a collapsible frame, the necessary bulge or rotundity to the periphery of the barrel. In working horizontally on said slideways *f* said sweeps come together and separate, the latter movement occurring after the staves are in position, trimmed, and provided with truss-hoops, and thus said barrel may be removed from the

machine. This movement of sweeps, however, is not new in this machine, but has been employed heretofore. The sweeps operate simultaneously, moving in opposite directions 5 under the influence or power derived from the main-shaft supports, which act as levers, as shown in Fig. 9, the fulcrums of which are on the sleeves *d*, arranged on the shaft *d*.

The lever-like supports *c c* are connected, 10 as at *i*, with the shorter sweeps *h'*, the connections being slotted to allow for the pivotal movement of the lever and the longer or rear sweeps *h''* being in train with the levers *c* by means of walking-beam levers *j* and connecting-rods *k k*. A hand-lever *l*, Fig. 1, and co-operating means are provided for easily 15 operating the levers *c* and their connections, but these do not form a part of my particular improvements, the subject of the present 20 patent. The lever-like supports *c c* are connected at their upper or free ends by a suitable connecting-bar *m*.

The bearings in the supports *c* for the driving-shaft *b* are shown at *n* in Fig. 9, where 25 one of said supports is shown to be recessed at one side to receive said shaft at a point corresponding with the axial center line of the sweeps *h* and opposite the ends of the correspondingly-recessed arms *o*, projecting 30 from the rear sweep *h''* laterally and then centrally, so as to lie outside the ends of the barrel and toward the shaft *b*, as indicated. The parts *c o* thus co-operate to form boxes 35 for the shaft *b*, which boxes have no independent fastenings requiring time for manipulation, but open automatically when the parts *c h''* are operated as described. The driving-shaft supports *c* are also provided with suitable brackets or bearings *p* (omitted 40 from Fig. 9, but shown in Figs. 1 and 14) for the shafts *q q*, on which are the circular saws or cutters for chamfering, crozing, and grooving the stave ends after the staves are in position to form the barrel and before said barrel is removed from the machine. Said circular saws or cutters are arranged to work 45 simultaneously, being given a longitudinal movement by which they are presented to the staves by a hand-ratchet *r*, working on bearings formed on a slide *s* and engaging a rack *t* on a slide *t'*. The slide *s* carries the cutters toward the end of the barrel when operated by the hand-ratchet *r*, and the slide *t'*, when operated by the screw *u*, regulates the depth 50 of the groove in which the heads of the barrel are inserted.

Referring to Figs. 12, 13, and 14, where the preferred construction is illustrated in detail, it will be observed that the trimming and 60 chamfering cutter *v* and its connections are coupled to the grooving and crozing cutter *v'*, so that the two operate together when operated by the hand-ratchet *r*. Each coupling consists of a link *w*, which extends from one 65 saw-spindle *q* to the other, as shown in Figs. 12 and 14, washers *w'* being employed to secure the desired adjustment. Pulleys 33 give

rotary motion to the shafts *q* and circular cutters, motion being transmitted thereto from the pulley-shaft *d* by belts 4, Fig. 1, in any 70 suitable manner. The shafts *q* slide longitudinally in the pulleys 3 to shift the cutters, the pulleys 3 remaining in position to properly receive power from the belts, said shafts being provided with suitable feathers or keys 75 to prevent independent rotary movement.

By means of the simultaneous movement of both the trimming and chamfering and the crozing and grooving cutters great exactness and uniformity are secured in the shaping of 80 the staves, and by moving the boxes in which the shafts rotate longitudinally with said shafts the latter are prevented from springing or bending, and as a result a true circular groove is produced, and the danger of 85 twisting off the ends of the spindles because of lateral pressure on the cutters is greatly reduced or entirely avoided.

In arranging the staves in position I employ, in connection with the sweeps *h' h''*, a 90 collapsible frame, (shown more clearly in Figs. 2, 3, 6, 7, and 8,) the sweeps lying outside of the barrel and the said frame on the inside. A collapsible frame in a similar position has been employed before; but the construction of the one hereinafter described is 95 new and useful in that it is stronger to resist the great pressure brought to bear thereon and in holding the staves true to correct position, so that the grooves, &c., will be properly formed by the cutters.

Upon the main driving-shaft *b*, between the bearings for the same, provided by the supporting-levers *c c*, are arranged disks 5 5. These are firmly keyed to the shaft and rotate therewith. Between said disks is arranged a sleeve 6, which is loose on said shaft, and thus is allowed an independent movement thereon. At one end of said sleeve 6 is keyed a gear-wheel 7, which meshes with 105 a series of small pinions or cog-wheels 8, Figs. 2, 7, and 8, strapped to the inside of one of the disks 5 and arranged on arbors 9, which have bearings in the straps and said disks and extend through the latter, from whence 115 said arbors project and are provided with angular heads 10, adapted to receive a hand-crank, by which said pinions 8, gear-wheels 7, and sleeve 6 are turned by hand when the frame is to be collapsed or extended. The 120 disks 5 also provide bearings for a series of shafts 11, which extend from one disk to the other in lines parallel with the main shaft, but at a distance therefrom. Suitable means are provided for securely holding said shafts 125 11 in place. On the sleeve 6 are also keyed two gear-wheels 12 12, the teeth of which are not continuous, but at points corresponding in number with said shafts 11 the teeth are missing, as shown in Figs. 3 and 6. The said 130 gear-wheels 12 12 are provided with long inwardly-extending hubs 13, on which are keyed star-wheels 14 14, the gear-wheels 12 and star-wheels 14 being thus movable to-

gether. On the shafts 11, adjacent to the gear-wheels 12, are two sets of pivotal interior stave-supports, the supports of one set alternating with the supports of the other. 5 The supports 15 have cogs 16, which mesh with the cogs of the gear-wheels 12. Said stave-supports 15 are angular in general outline in side view, as in Figs. 3 and 6, the pivotal bearings being on the inner arms 18 thereof, having the cogged segments 16. The outer arms 17 of the supports are segmental and, together with alternating segments of the supports 21, form, when the frame is distended, the circular bearings on which the 15 staves are arranged to form the barrel-body. The outer or free ends of the segment-arms 17 are, when in their distended positions, adapted to rest upon the outer extremities of the rays of the star-wheel 14, the said rays 20 serving as supports, which give great firmness and rigidity to the said arms and render them capable of resisting great pressure.

Fastened upon the gear-wheels 12 are locking-arms 19, adapted to engage at certain 25 times the hubs 20 of the stave-supports 15, the latter being cut away on lines concentric with the shaft *b* at one side of their peripheries to receive the ends of said arms 19, so that the said hubs are locked, and the supports 30 15 are prevented from turning on their shafts independently when the cogs 16 are brought to points of coincidence with the spaces formed in the wheels 12 by the missing teeth, as will be hereinafter more fully described. Upon the same shafts 11 with the stave-supports 15 are other stave-supports 21, similar to those first described, excepting that they are without cogged segments engaging with the gear-wheels 12. 35 Said supports 21 are operated by the supports 15, the latter being provided with lateral projections 22, which underlie the outer segments 23, as shown in Fig. 8, and thus when said supports 15 are turned to their distended 40 positions the projections 22 slide along the under sides of said segments 23 and force the latter to their outward positions to make complete circles. Reverse action of the supports 21 is occasioned by the springs 24, which connect 45 said supports 21 preferably with the star-wheel, so that when the projections 22 move backward the said springs may act to draw said supports 21 to their folded or collapsed relations. The supporting-rays of the 50 star-wheel are also provided with lateral projections 25, Fig. 8, which engage the projections 22 of the arm 15, which projections underlie the segments 23 of the stave-support 55 21. These projections are arranged and the movements timed so as to come into engagement at the proper moments and be out of the way at other times when the parts are being collapsed.

In operating the collapsible frame after 60 the staves have been arranged in position, trimmed, and provided with truss-hoops to enable the barrel to be removed therefrom I

first open the sweeps by operating the hand-lever 1 or in any other manner common in the art. I then take a hand-crank and apply 70 it to the angular head 10 of one of the arbors 9, the crank being applied to that arbor which happens to be free of obstruction, and particularly at one side or the other of the arms 15 toward the rear of the machine. By turning 75 said arbor a pinion 8 is turned, and this, engaging the gear-wheel 7, keyed to the sleeve 6, transmits motion to said sleeve 6. In turn motion is transmitted from said sleeve to the hubs 13 and gear-wheels 12, which work with 80 the said sleeve. With the hubs 13 and the sleeve 6 also work the star-wheels 14 and locking-arms 19. The rays of said star-wheel move from beneath the projections 22 of the stave-supports 15, and the locking-arms 19 85 move from under the flattened bearings of the hubs 20 of said stave-supports 15. At the initial time of movement of the said rays and locking-arms from beneath their coöperating bearings the gear-wheels 12, which at 90 four (more or less) points on the peripheries thereof have missing cogs or teeth, are disengaged from the toothed or cogged segments 16, but immediately upon the said locking-arms and supporting-rays passing from their 95 locking and supporting positions the teeth or cogs of the gear-wheel 12 intermesh with the cogs or teeth 16 of the segments 16, and as a result the supporting-arms 15 are turned inwardly on their fulcrum or pivotal bearings 100 11 to their collapsed positions, as shown in Fig. 6. The action of the arms 15 serves to remove the projections 22 from supporting or holding relation from the stave-supports 23, and the springs 24 are allowed to act to draw 105 on said stave-supports 23 to draw them also to their collapsed positions.

To open the frame again, the operation of the crank and parts in train therewith is simply reversed, the projections 22 of the 110 stave-supports 15 sliding on the under side of the stave-support segments 23 and pushing the latter outward until the parts are all in position to produce the continuous circles, as will be understood.

The operation of the parts thus described 115 leaves the barrel loose on the frame, so that it can be moved easily endwise along the shaft *b*. To enable said barrel to be removed from said shaft, which is a continuous one, and therein differs from those of certain machines heretofore in use in which the frame was pivoted upon two independent shafts constructed to allow the removal of the barrel between. This prior construction, however, was the occasion of weakness in the machine and the consequent imperfections in the results there- 120 125 of already referred to.

In my construction the shaft is, as before indicated, continuous, the one shaft having 130 bearings at opposite sides of the barrel, so that great rigidity and strength are required. To enable the barrel to be removed from the shaft easily and with convenience, I provide the

said shaft with what I term an "outside" bearing 26, arranged at one side of the machine at a little distance from the body of the machine, the distance between said body of the machine and said bearing being at least equal to the length of the barrel, so that said barrel may be arranged temporarily therebetween. The said bearing is in sections, the portion 27 being firmly secured to the floor or other fixture and provided with a pivot or fulcrum 28 and the portion 29 being, lever-like, fulcrumed on said pivot and having at one end a weight 30 and at the opposite upper end a socket 31, into which the shaft may rest. When the barrel is to be removed, the lever 1 is turned down, as already described, and the sweeps *h* moved oppositely and horizontally from the levers *c*, so that the bearing-boxes formed by the arms *o* and said levers *c* are opened. Were it not for the outside bearing 26, it is evident that the shaft would bend or fall at its end on which the barrel is arranged, the bearings in the supports or stands *a' a'* being insufficient; but by having the supplemental or outside bearing this danger is avoided. The sweeps being opened the barrel is pushed along the shaft to the outside bearing, after which the sweeps are again closed and the shaft *b* again clasped by the bearings *o c*, as will be apparent.

While a new set of staves are being fed to the machine, the barrel on the outer end of the shaft is removed by simply raising the weight 30 and turning down the arm of the lever 29. After removal the bearing assumes a shaft-supporting position automatically.

In feeding the staves to the machine, whereby they are made to lie side by side as ordinarily found in barrels, the operator opens up the forward sweeps by turning the hand cam or lever 32 and opening the gates 33, which close the feeding apertures or entrance-ways for the staves. The central sweeps are not ordinarily gated, but the feeding-entrances remain constantly open.

Gates, while not broadly new, have been of a construction and arrangement which materially interfered with a quick and convenient feeding of the staves. In the present case I simply pivot the gates upon the upper ends of the forward sweeps, so that by turning them backward they lie away considerably from the point of entrance beneath the feed-rollers 34 and hang down, so as to be out of the way of the workman in positioning the staves prior to insertion.

To hold the gates down upon the staves last inserted after the annular space formed by the interior frame and outer sweeps are fully occupied by staves, I employ the hand cams or levers 32, which are loosely fulcrumed or pivoted on the feed-roller shaft 35. By simply turning the handles of said lever forward after closing the gates said levers are pressed down against the gates, and the latter press the last-inserted staves firmly down in place,

so that the said staves may be subjected to the action of the cutters when turned by the rotary action of the feed-rollers 24 and the 70 interior frame rotating with the shaft *b*.

The feed-rollershaft 35 is of novel construction and facilitates operation. In Figs. 4 and 5 said shaft is shown in detail at its end receiving power from the train of cog-wheels 75 36, communicating with the main driving-shaft *b*. In a prior device the feed-shaft was a single bar of metal operating in connection with a cup working with one of said gear-wheels. The different pressures due to variations in the thicknesses of the staves variously affected the pressure of the shaft upon the sides of the said cup, so that when the staves were thick and the pressure great it was difficult, if not impossible, to disconnect 85 the shaft from said cup, and much time was frequently lost in attempting the separation. In the present case I dispense with the cup and employ with the cogs 36 a shaft-section 37, which works in the bearing 38 of a bed 90 *a* or a stand *a'* thereof. At the inner end of said shaft-section the same is provided with an annular end or head 39, which works in a correspondingly-shaped socket of a coupling 40, the said socket being opposite a transverse 95 slot 41 in the other end of said coupling, which slot receives a tongue 42 of the body portion of the feed-roller shaft. The tongue 42 has a freedom of movement or play in said slot, so that the pressure due to the difference in 100 the thickness of the staves above referred to cannot cause a binding of parts and a difficult separation preliminary to opening the sweeps. When said sweeps are to be opened, the said coupling 40 is simply pushed upon 105 the angular head 39 away from the tongued shaft, so as to clear the same when moving the feed-roller shaft with the parts *c c*.

The operation of the particular improvements of my invention having been quite fully described in connection with the description of the construction and arrangement of parts, further description is deemed to be unnecessary.

Having thus described the invention, what 115 I claim as new is—

1. In a barrel-machine, the combination with a continuous shaft, extensible entirely through the barrel, means for rotating said shaft, permanent bearings at one end of said shaft, a separable bearing toward the other end of said shaft, and a supplemental bearing arranged and constructed to admit the passage of the barrel-body therewith, and a collapsible frame arranged on said shaft, substantially as set forth, for the purposes stated. 125

2. In a barrel-machine, the combination with the sweeps and collapsible stave-supporting frame, and the shaft *b*, extending out from the machine proper a distance equal to 130 or greater than the length of a barrel, of a permanent bearing at one end of said shaft, a hinged supplemental support or bearing 26, at the opposite projecting or free end of said

shaft and separable bearings permitting a passage of the barrel to said projecting end of the shaft, all substantially as set forth.

3. In a barrel-machine, the combination 5 with the shaft *b*, and means for rotating the same, of permanent bearings toward one end of the shaft, separable bearings toward the other end of said shaft, an intermediate collapsible stave-support, outside sweeps separable as described, and a hinged supplemental support, all arranged and combined, substantially as set forth.

4. In a barrel-machine, the combination 15 with the collapsible frame and its shaft, and means for rotating the same, of sweeps, one of which is provided with a shaft-supporting arm and lever-like sweep-operating shaft-supports, separable from said shaft and coöperating with said shaft-supporting arm to form 20 a box, substantially as set forth.

5. In a barrel-machine, the combination 25 with the collapsible frame and its shaft, and means for rotating the same, of sweeps, one of which is provided with an arm *o*, recessed at its extremity to receive the said shaft, levers *c*, in train with said sweeps, and coöperating with said arm to form a box for said shaft, said lever being movable from said arm when operating said sweeps to open the 30 same, and a supplemental bearing at a distance from the box, formed by said arm and lever, substantially as set forth.

6. In a barrel-machine, the combination 35 with the shaft, collapsible frame and means for operating the same to secure a rotary movement, of separable sweeps, one of which has a shaft-arm *o*, a lever operating said sweeps, and having a bearing coöperating with said arm to form a box, and a weighted 40 supplemental bearing distant from said box, substantially as set forth.

7. In a barrel-machine, the combination 45 with the shaft, collapsible frame and means for rotating the same, of separable sweeps one of which has the arm *o*, a lever-like sweep-operating shaft-support separable from said arm, a supplemental shaft support or bearing, also separable from the shaft, a feed-roller shaft and means for operating the same, feed- 50 rollers for forcing the staves between the sweeps, and collapsible frame, and cutters for trimming the ends of the barrel, before removal from the machine, substantially as set forth.

55 8. In a barrel-making machine, the combination with the shaft, collapsible frame, and means for operating the same, of front and rear sweeps separable from one another, and having feed-openings between, and means 60 for operating said sweeps, of gates hinged to said sweeps, and cams for forcing said gates upon the staves, substantially as set forth.

9. In a barrel-machine, the combination 65 with the shaft, collapsible frame, and means for rotating the same, of front and rear sweeps and means for operating the same, of hinged gates 33, and cam-levers for forcing said

gates upon the barrel-staves, substantially as set forth.

10. In a barrel-machine, the combination 70 with the shaft *b*, collapsible frame and means for rotating the same, of front and rear sweeps, and means for separating the same, a feed-roller shaft, feed-rollers and means for operating the same, gates hinged upon the sweeps 75 for closing the feed-openings, and cam-levers fulcrumed upon said feed-roller shaft, and engaging said gates to force the same upon the staves, substantially as set forth.

11. In a barrel-machine, the combination 80 with a bed-plate having stands *a'*, the shaft *b*, collapsible frame and means for operating the same, of sweeps and means for operating said sweeps, lever-like swinging arms, feed-rollers, a sectional feed-roller shaft one section of 85 which is mounted in the lever-like arms and the other in one of the stands *a'*, and means for operating said shaft, the sections of said shaft being separably coupled together, and a sliding coupling 40, substantially as set 90 forth.

12. In a barrel-machine, the combination 95 with the bed-plate having stands; the shaft *b*, collapsible frame and means for operating the same, of sweeps and means for operating the same, lever-like swinging arms; feed-rollers, a sectional feed-roller shaft, the sections of which have bearings in said stands and swinging arms and a coupling having an 100 end slot allowing an independent lateral play of the section of said shaft therein, substantially as and for the purposes set forth.

13. In a barrel-making machine, the combination with bed-plate having stands and lever-like swinging arms; the collapsible frame, 105 sweeps and means for operating the same, of a feed-roller shaft and its feed-roller, said shaft being in sections having bearings in the stand and swinging arms, one of which is in 110 constant train with means for rotating said shaft, and the other is allowed a lateral play with reference to the first, and said means for rotating said shaft, substantially as and for the purposes set forth.

14. In a barrel-making machine, the combination 115 with the bed-plate having stands and the swinging arms, a collapsible frame, sweeps and means for operating the same, of a feed-roller shaft, and feed-roll for forcing the staves in position between said frame 120 and sweeps, one section of the shaft having bearings in one of the stands and being transversely slotted and permanently in train with the operating means, and the other having bearings in said swinging arms and having a 125 lateral play in the slot of said section, substantially as set forth.

15. In a barrel-making machine, the combination with the bed-plate having stands and a swinging arm, a collapsible frame, sweeps 130 and means for operating the same, of a sectional feed-roller shaft having bearings in said stands and arms, and a coupling 40, the latter having an angular central opening and

sliding on the angular head of one section, and having a slot to receive and allow play to the other section while rotating the same, and means for rotating said feed-roller shaft, substantially as set forth.

16. In a barrel-making machine, the combination with the sweeps, collapsible frame, sweep-operating lever, and means for connecting and operating the same, of brackets ¹⁰ *p* and *p*, boxes *s* and *s*, carrying spindles *q*, *q*, in turn carrying circular cutters *v*, *v'*, the spindles *q*, *q*, being coupled or connected to occasion a simultaneous movement of the two cutters by one operation of the hand, and a ¹⁵ hand lever for operating said boxes to bring them into or out of engagement with the barrel-body, substantially as set forth.

17. In a barrel-machine, the combination with the sweeps, feed devices and means for ²⁰ operating the same, of a shaft *b*, and a collapsible frame, comprising two sets of lever-like segments, adapted to be turned pivotally to bring the segmental portions to or from a position to form a complete circle to receive ²⁵ the staves, the segments of one set alternating with those of the other, transmitting movement thereto, and means for turning said lever-like segments and holding them in position, substantially as set forth.

18. In a barrel-machine, the combination with the sweeps, feed devices and means for operating the same, of a shaft *b*, and a collapsible frame, comprising two sets of lever-like segments, the segments of one projecting ³⁵ into engagement with the others, and raising the same to positions to form a complete circle therewith, means for operating said segments, means for drawing the second set of segments, operated upon by the segments of ⁴⁰ the first set, to the collapsed positions, and means for supporting said segments in their distended positions, or positions forming the circle, substantially as set forth.

19. In a barrel-machine, the combination ⁴⁵ with the sweeps, and feed devices and means for operating the same, of a shaft *b*, disks *5*, *5*, series of shafts *11*, *11*, *11*, segments fulcrumed thereon and movable oppositely on said shafts *11*, the segments of one set being ⁵⁰ movable under the power of the segments of the others, and means for operating said parts, and star-wheels, the arms or rays of which underlie the segments to hold them in distended positions, substantially as set forth.

20. In a barrel-machine, the combination with the sweeps and means for operating the same, of a shaft *b*, disks *5*, sleeve *6*, shafts *11*, lever-like segments, gear-wheels for turning said segments simultaneously, and means ⁶⁰ for holding said segments in distended position, substantially as set forth.

21. In a barrel-machine, the combination with the sweeps, and means for operating the same, of a shaft *b*, disks *5*, keyed to the shaft, ⁶⁵ a sleeve on said shaft between said disk, and loose on said shaft, a gear-wheel keyed to said sleeve, means for turning said gear-

wheel by hand, a series of shafts *11*, having bearings in said disks, and having segment-levers thereon, means for turning said segment-levers on said shafts, star-wheels supporting said segment-levers, and means for locking said segments, substantially as set forth.

22. In a barrel-machine, the combination ⁷⁵ with the sweeps, and means for operating the same, of a shaft *b*, disks *5*, *5*, keyed to said shaft, a sleeve arranged loosely on said shaft between said disks, a gear-wheel keyed to said sleeve, a series of cog-wheels meshing ⁸⁰ with said gear-wheel, and working on arbors with angular heads extending from the outer side of one of said disks, a gear-wheel *12*, with missing teeth, two sets of lever-like segments, one set of which has segmental arms ⁸⁵ provided with teeth which engage the teeth of said gear-wheel *12*, and the other set engaging the first and raised or distended thereby, springs for drawing the second set of segments to their collapsed positions, and ⁹⁰ means for supporting said segments in their said distended positions, substantially as set forth.

23. In a barrel-machine, the combination with the sweeps and means for operating the same, and a suitable feeding device, of a shaft and a collapsible frame thereon, adapted to receive the staves when distended, said frame including a series of pivotal segments having segmental portions co-operating to form a ¹⁰⁰ circle on which the staves are arranged, and inwardly-extending arms or portions providing pivotal bearings, the alternate members of the series having segmental arms geared to a common source of power, and having ¹⁰⁵ extensions engaging the other members of the series to operate the same, said common source of power, and means for operating said parts, all substantially as and for the purposes set forth.

24. In a barrel-machine, the combination with the sweeps and means for operating the same, the feed-rollers and circular cutters, and means for rotating the same, of a shaft adapted to extend through the barrel ¹¹⁵ continuously, and having bearing between which the barrel may be formed, the bearings at one end of said barrel being separable from said shaft to allow the endwise passage of the barrel, and a collapsible frame arranged ¹²⁰ on said shaft, said collapsible frame comprising series of pivotal segments, the segments of one series alternating with those of the other series, and engaging the same to raise them to a position to form circles on which ¹²⁵ the staves are arranged to form the barrel-body, radial supports also arranged on said shaft and movable beneath the segments to hold them in the said circles, and locking-arms movable with said radial supports to ¹³⁰ lock said segments against pivotal action when distended, and means for connecting and operating said parts, substantially as and for the purposes set forth.

25. In a barrel-machine, the collapsible frame over which to form the barrel-body, which comprises the shaft *b*, end disks 5, 5, shafts 11, having bearing in said disks away from said shaft *b*, a sleeve 6, on said shaft *b*, between said disks 5, 5, a gear-wheel 7, fixed to said sleeve at one end thereof, pinions 8, on arbors 9, having bearings in one of said disks, and being adapted to be turned by a hand implement or tool, gear-wheels 12, 12, with missing teeth and hubs 13, locking-arms fastened to said gear-wheels 12, 12, supporting-arms 14, keyed upon said hubs 13, a series of segments 15, pivoted upon shafts 11, and provided with toothed segments engaging the teeth of the gear-wheels 12, and lock-bearings 19, a series of segments 21, pivoted on said shafts 11, and engaging by the segments 15, and springs 24, for collapsing the segments 21, all said parts being arranged and combined, substantially as set forth.

26. In a barrel-machine, the combination with a central shaft *b*, and a series of shafts 11, arranged therearound at a little distance therefrom, and carrying collapsible segments over which the barrel-body may be formed, of a series of pinions 8, 8, a common gear-wheel 7, in train with said pinions and said collapsible segments, whereby in turning one of said pinions, all of said segments will receive power and move to new positions simultaneously and together, substantially as set forth.

27. In a barrel-machine, the combination with a central shaft *b*, and a series of shafts 11, assembled around the same at a little distance therefrom, and carrying pivotal segments which are angular in general outline, the inwardly-extending arms being arranged on said shafts 11, of a series of pinions also

disposed around said central shaft, a common gear-wheel meshing with each of said pinions, and in train with said collapsible segments, whereby the latter move simultaneously and together, and means for supporting and locking said segments, substantially as and for the purposes set forth. 45

28. In a barrel-machine, the combination with a central shaft *b*, a series of shafts 11, arranged therearound, a sleeve arranged on said shaft, and two series of segments pivoted and movable oppositely on said shafts 11, the segments of one of said series having lateral projections 22, extensible under the segments of the other series, means in train with said sleeve and segments for operating the latter, and supporting-rays 14, for holding said arms in distended positions, substantially as set forth. 50

29. In a barrel-machine, the combination with a central shaft *b*, a series of shafts 11, arranged around said central shaft, a sleeve arranged loosely on said central shaft, two series of segments movable oppositely on said shafts 11, the segments of one series having lateral projections engaging and operating those of the other series, and star-wheels arranged to move with said sleeve, and having projections 25, adapted to engage the projections 22 and hold, each, a pair of oppositely-moving segments, substantially as shown and described. 65 70

In testimony that I claim the foregoing I have hereunto set my hand this 23d day of October, 1895.

ROBERT NAWRATH.
